HIS ATTORNEYS.

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed August 2, 1926. Serial No. 126,454.

This invention relates principally to that type of flexible outside metal car roof wherein light gage roofing sheets are loosely connected along their adjacent margins by weather proofing seam covers that permit relative movement of said roof sheets to a limited extent so as to be able to accommodate themselves to the distortions of the car body.

10 The principal object of the present invention is an improved seam construction that will secure a pivotal movement of the roof sheets whenever there is movement thereof. Other objects are simplicity and cheapness 15 of construction, compactness and economy in design and ease of assembly.

The invention consists principally in connecting the spaced margins of adjacent roof sheets by means of a weather proofing seam 20 cover that has a separate pivotal connection with each of said sheets. The invention further consists in the parts and in the combinations and arrangements of parts hereinafter described and claimed.

25 In the accompanying drawing, which forms part of this specification and wherein like symbols refer to like parts wherever they occur,

Fig. 1 is a plan view of the flexible outside metal car roof embodying my invention;

Fig. 2 is a transverse section through one of the side seams on line 2—2 in Fig. 1;

Fig. 3 is a transverse section through the roof at the eaves on the line 3—3 in Fig. 1;

Fig. 4 is a fragmentary plan view, showing the pivotal connections between the ridge seam cap and the roof sheets; and

Fig. 5 is a vertical cross section through the ridge seam on the line 5—5 in Fig. 4.

Referring to the accompanying drawing, my invention is shown in connection with a car having wooden roof sheathing 6 supported on side plates 7 and a ridge pole 8. Metal roof sheets 9 are arranged on the roof sheathing 6 side by side in two rows on opposite sides of the ridge, the two rows of roof sheets being spaced apart at the ridge and the sheets in each row being spaced apart at their sides. The roof sheets on opposite sides of the ridge are arranged in alignment transversely of the car; and mullions or battens 10 are secured to the car in the spaces between the adjacent side

margins of said sheets. The mullions 10 55 extend transversely of the car from eaves to eaves thereof and are of less width than the spaces between the adjacent side margins of the sheets so as to permit a limited angular adjustment of said sheets between 60 said mullions.

The ridge and side margins of the roof sheets 9 are preferably turned up and then bent inwardly and downwardly over the body portions of the sheets to form upstanding hook-shaped side and ridge seam flanges 11 and 12, respectively. The eaves ends of the sheets are doubled under to form hook flanges 13 that loosely engage the doubled over hooked flanges 14^a of angle flashing 70 strips 14 that are secured to the eaves of the car, such arrangement serving to loosely retain the sheets on the car at the eaves. The adjacent side seam flanges 11 of the roof sheets, together with the mullions 10 75 located therebetween, are preferably covered by inverted channel-shaped transverse or side seam covers or caps 15 that extend from eaves to ridge of the car and rest on said mullions. The side seam covers 15 80 have inwardly and upwardly extending hook flanges 16 at their lower edges that loosely interlock with the upstanding side seam flanges 11 of adjacent sheets. The eaves ends of the side seam covers are 85 loosely held in position preferably by extensions 17 at their eaves ends, which extensions are turned down over the eaves ends of the mullions 10 and are thence turned under the doubled eaves corners 13 of the 90 roof sheets and hooked into the doubled backed flanges 14^a of the eaves flashing strips 14.

The spaced ridge ends of the roof sheets are connected by pressed metal ridge seam 95 covers or caps 18 of substantially inverted channel-shaped section. The ridge seam covers or caps 18 straddle the adjacent ridge flanges 12 of the roof sheets and have outstanding base flanges 19 that rest on the 100 body portions of said sheets inside the ridge and side seam flanges thereof. The adjacent ends of the ridge seam covers 18 and the transverse seam covers 15 are held in position on the car preferably by means 105 of the usual four-way center or corner caps 20 that are secured in position by means of vertical bolts, 21, which also secure the

running board saddles (not shown) in position.

The base flanges 19 of the ridge seam covers 18 are provided midway of their length

5 with upstanding circular pivot bosses or inverted cups 22 which fit over similarly shaped upstanding pivot bosses or projections 23 pressed in the ridge end portions of the roof sheets midway of the said margins thereof.

10 As shown in the drawing, the seam covers are strengthened by ribs 24 that extend from the inner edge of the bosses 22 to the side walls of said covers. By this arrangement, the roof sheets are pivotally held down on the roof by the cooperating pivot bosses on the ridge ends of said sheets and the base flanges of the ridge seam covers and are thus adapted to accommodate themselves to the distortions of the car body

15 20 by pivoting or sluing about points located near the middle of their ridge ends. Said arrangement also provides a separate pivotal connection between each sheet and the ridge seam cover therefor, whereby each sheet slues or oscillates individually on the fixed seam cover therefor; it also serves to properly center the sheets between adjacent roof mullions; and it also serves to maintain a proper spacing of the ridge ends of said sheets.

25 30 An important advantage of the above arrangement is that it secures a sluing or pivotal movement of roof sheets, which are spaced apart along their ridge margins, without the use of separate pivot saddles or clips and thereby saves the cost of such members. Other advantages of the present construction are its simplicity and cheapness of construction and the ease with which it may be assembled.

35 40 The invention is not restricted to the precise shapes and arrangements of parts that are shown and described.

What I claim is:

45 50 1. A flexible car roof comprising roof sheets spaced apart along the adjacent margins, a seam cover covering the adjacent marginal portions of said sheets, and a separate pivotal connection between said seam cover and each of said roof sheets, said connection preventing bodily movement of said sheets longitudinally of said seam cover.

55 60 2. A flexible car roof comprising roof sheets, a seam cover covering the adjacent marginal portions of said sheets, and a separate pivotal connection between said seam cover and each of said sheets, said connec-

tion preventing bodily movement of said sheets longitudinally of said seam cover.

65 3. A flexible car roof comprising roof sheets spaced apart along their adjacent margins and provided along said margins with upstanding seam flanges, and a seam cover straddling the adjacent flanges of said sheets and having separate pivotal connections with the body portions thereof.

70 75 4. A flexible car roof comprising roof sheets spaced apart along their adjacent margins and provided along said margins with upstanding seam flanges, and a seam cover straddling the adjacent seam flanges of said sheets and having base flanges, said roof sheets being provided with pivots and the base flanges of said seam covers being provided with bearings for the roof sheet pivots to turn in.

80 85 5. A flexible car roof comprising roof sheets spaced apart along their adjacent margins and provided with pivot bosses, and a seam cover covering the adjacent margins of said sheets and having base flanges provided with bosses that fit over the pivot bosses of said roof sheets.

90 95 6. A flexible car roof comprising roof sheets spaced apart along their adjacent margins and provided with upstanding pivots near said margins, and a seam cover covering the adjacent margins of said sheets and having outstanding base flanges provided with pivot bearings adapted to receive the pivot bosses of said roof sheets.

100 7. A seam cover for a car roof, said seam cover having a lateral extending flange provided with a pivot member adapted to cooperate with the pivot member of a car roof sheet.

8. A seam cover for a car roof, said seam cover having lateral extending base flanges with pivot recesses adapted to receive the pivots of car roof sheets.

105 9. A seam cover for a car roof, said seam cover being of a substantially inverted channel-shaped section and having lateral base flanges at the lower edges of its side walls, said flanges being provided with pivot bosses adapted to cooperate with the pivot bosses of car roof sheets.

110 10. A seam cover for a car roof, said seam cover being provided with a pair of pivot bosses adapted to cooperate with the pivot bosses of a pair of roof sheets.

Signed at New Kensington, Pa., this 26th day of July, 1926.

CHARLES DAVID BONSALL.
